signors to Atmospheric Nitrogen Corporation,
New York, N. Y., a corporation of New York

Application October 10, 1930, Serial No. 487,886

3 Claims. (Cl. 103—40)

The present invention relates to pumps generally, and more particularly to force-feed lubricator pumps adapted to periodically supply variable quantities of oil to parts of machines requiring

5 a constant supply of lubricant.

The principal object of the invention lies in the provision of a pump unit comprising a piston and a cylinder together with co-operating mechanism constructed and arranged to positively deliver measured quantities of oil, variable at will, to one or more parts of a machine operating under such conditions that comparatively high pressures exist at the point or points where the lubricant is required. Although it is to be understood 10 that the pump described herein by way of example is of general application, the invention particularly contemplates the provision of a lubricator adaptable for use in conjunction with heavy duty compressors working at pressures of 15 say 2,000 pounds per square inch and upwards.

Briefly, the invention comprises a pump unit having a fixed piston and a reciprocating cylinder, a discharge valve immediately associated with the fixed piston and an inlet valve in a housing moving with and forming a part of the reciprocable cylinder. In the present embodiment of the invention, the construction is such that on each suction stroke of the pump a full charge is drawn into the pump cylinder, and during the 20 discharge stroke, the closing of the cylinder inlet valve may be delayed to cause, before the closing of the inlet valve, the return of a portion of the full charge in the cylinder to the pump reservoir, and, after the closing of the inlet valve to effect the 25 discharge of the balance of the oil in the cylinder into the conduit connecting the pump unit to the part or parts of the machine to be lubricated. To this end, the invention includes a lever which acts directly to hold the inlet valve open during 30 certain portions of the discharge stroke of the pump, and a relatively fixed cam which controls the action of the lever and which may be adjusted to cause the lever to permit closing of the inlet valve at different times during the discharge 35 stroke of the pump and thus vary the output of the pump.

For a more complete understanding of the nature and objects of the invention, reference may be had to the following detailed description 40 taken in connection with the accompanying drawings in which

Fig. 1 is a plan view of the pump casing with the pump units removed;

Fig. 2 is a vertical section on the line 2—2 of 45 Fig. 1;

Fig. 3 is a longitudinal vertical section taken approximately on the line 3—3 of Fig. 1, and showing the main shaft together with the shaft operating ratchet;

Fig. 4 is an elevation of one of the operating ratchets with certain parts removed, taken approximately on the line 4—4 of Fig. 3;

Fig. 5 is a vertical section through one of the pump units;

Fig. 6 is a detail, partly in section, of the valve 10 housing block on the lower end of the cylinder;

Fig. 7 is a view of the block approximately on the line 7—7 of Fig. 6;

Fig. 8 is an end view of the block looking from the right in Fig. 6 and;

Figs. 9 and 10 are details showing respectively a cinch head bolt and an associated cinch head.

Referring to the drawings, the reference numeral 10 indicates generally a casing or reservoir for the oil which is to be delivered to the points of use by the several pumping units. The casing 10 is substantially rectangular in plan, and is provided with a series of transverse partitions 11 forming separate compartments for each of the pump units. Cut-out portions 12 in the partitions serve to decrease the weight of the reservoir casting and provide communication between the several compartments so that the oil level is the same in all parts of the reservoir. The bottom of the casing 13 slopes toward the front 20 affording, along one lower edge of the reservoir, a channel from which the oil may be completely withdrawn from the reservoir through an opening 14. As shown in Fig. 1, and in detail in Fig. 2, the front vertical wall of the casing is formed 25 with an indentation 15 to accommodate the glass tube 16 for an oil gauge. The interior of the gauge communicates with the oil reservoir through the opening 17, and the tube 16 is held firmly in place by a plug 18 threaded into the top of the upper edge of the reservoir wall, and having a central aperture 19 providing communication between the interior of the tube and the atmosphere. The compartment at the right end 30 of the casing may conveniently be used to supply 35 oil to the reservoir, and for this purpose, as shown in Fig. 3, is equipped with a strainer 21 and a removable cover 22.

The end walls of the reservoir and the partitions are cast and machined to provide bearings 24 for the drive shaft indicated generally at 25. The shaft bearings are made comparatively large so that all surfaces of the several pump-operating eccentrics 27 may lie entirely within the circumferences of the shaft bearings, thus permit- 45 50 55

ting the shaft 25 to be placed in and removed from the reservoir endwise. Leakage from the oil reservoir around the ends of the shaft is prevented by packing 30 and the glands 31.

5 Both ends of the shaft project some distance beyond the walls of the reservoir, and have mounted thereon the shaft operating ratchets indicated generally at 33 and 34. Normally, the pumping units are mechanically driven through 10 a suitable connection between the ratchet 33 and some part of the machine which the pump units are serving to lubricate. Referring to Figs. 3 and 4, the ratchet hub 35 is rigidly connected to the right end of the shaft by a suitable key 36. The ratchet case 37, having formed integrally therewith an operating arm 38, is rotatably mounted on the inner side of the ratchet hub 35. The ratchet cover 39 is likewise rotatably mounted on the ratchet hub, but, as shown in Fig. 3, 15 is positioned on the opposite side of an annular flange 40 projecting from the center of the ratchet hub. An annular hardened steel bearing ring 41, shown in elevation in Fig. 4, is set into and keyed to the case 37 by a short key 42. The cover 39 is attached to the case 37 by a series of 20 bolts 43. As indicated in Fig. 4, the flange 40 is provided on the periphery thereof with cut-outs 44 accommodating the hardened steel rollers 45, the surfaces of which engage respectively the 25 faces of the cut-outs 44 and the inner surface of the ring 41. The operating arm 38 is provided with several openings 52 to receive the end of an operating pin 53 to which may be attached a lever or arm, not shown, connected to some 30 reciprocating or rotating part of the machine. From the foregoing, it will be apparent that by reason of the construction described, including the ring 41, cut-outs 44 and the rollers 45, that movement of the operating arm 38 in a counter-clockwise direction, Fig. 4, effects a corresponding 35 rotation to the main shaft 25, and that a clockwise movement of the operating arm 38 imparts no movement whatever to the main shaft.

The ratchet 34 on the opposite end of the 40 shaft 25 is of substantially the same construction as that already described in connection with ratchet 33. However, the end of the operating arm 55 is provided with a handle 56 permitting manual operation of the ratchet 34 and the shaft 50 25 whenever necessary or desirable.

Cast on each of the end walls of the casing is 55 a pair of projections 57 adapted to receive a connecting pin 58 for rotatably supporting a hinge-like stop 59. As clearly indicated in Fig. 3, the stop 59 has on its underside a recess 60 to receive the end of a stop pin 61, set into the arm 55 of the ratchet 34. When the ratchet 34 is not in use, and the lubricator is being operated mechanically through the ratchet 33, the arm 60 60 of the ratchet 34 is maintained in an upward vertical position by the stop 59 as shown in Fig. 3. When it is desired to manually rotate the shaft, the stop 59 is initially raised to release the pin 61 and allow the arm 55 to be moved 65 from the vertical position. The stop may then be dropped downwardly to rest against the vertical edge of the casing out of the path of the pin 60. The right end of the casing, Fig. 3, is provided with a similar stop, not shown, for maintaining the arm 38 in a fixed vertical position 70 when the manual and power ratchets are interchanged.

Fig. 5 illustrates a transverse vertical section of the reservoir 10, and also a longitudinal vertical section through a pumping unit operating

in one of the compartments formed by the several partitions 11. The pump frame 65 is rectangular in plan, supports the pumping mechanism, and at the same time forms a cover for the particular compartment in which the attached pump unit is positioned. It will be understood that in the present illustration the reservoir 10 is designed to receive eight separate and distinct pump units, and that each unit is a duplicate of that shown and described in connection with Fig. 5.

The horizontal cover portion of each frame 65 is suitably bolted to the upper edge of the casing as indicated at 66 and 67. The frame 65 is formed so as to provide a downwardly projecting cylinder sleeve 68, and a similar downwardly projecting adjusting spindle sleeve 69. A supporting arm 70 projects vertically upward from the upper face of the frame, and terminates in an annular casting 71 adapted to receive the pump piston head 72. In the embodiment of the invention illustrated, the pump comprises a fixed piston 75, and a reciprocating cylinder 76 having a cylinder chamber 77.

The lower end of the piston head 72 is enlarged to form an annular shoulder 80 for engagement with the under side of the annular casting 71. Some distance upwardly toward the opposite end, the piston head 72 is externally threaded to receive an internally threaded nut 81 which bears against the upper surface of the annular casting 71 and, when tightened down, pulls the annular shoulder 80 on the lower end of the plunger head against the under side of the casting 71, thus holding the plunger head 72 firmly in place. The upper end of the fixed piston 75 is tapered and pressed into the central vertical channel 83 in the piston head 72. Piston 75 is provided with a longitudinal duct 84 effecting communication between the cylinder chamber 77 and the valve chamber formed in the piston head 72.

An outlet valve 86 is seated in the valve chamber in the piston head 72, and is normally held against the valve seat by a spring 87 bearing at one end against the upper side of the valve and at its other end against the lower side of the cinch head bolt 88 shown in detail in Fig. 9. The cinch head bolt 88 is threaded on its lower end to fit into a corresponding threaded portion in the upper end of the outlet valve chamber. Oil discharged by a pump unit is conducted to the part of the machine to be lubricated through a suitable pipe connection threaded into the tubular section 89 in the cinch head 90 shown in detail in Fig. 10. The cinch head 90 has a vertical passage 91 to receive cinch head bolt 88 for attaching the cinch head to piston head 72. When the cinch head bolt is screwed down as far as possible, the cinch head, the cinch head bolt and the piston head are tightly clamped together in the position shown in Fig. 5. The under side of the head of the bolt and the annular extension 92 on the cinch head are seated in copper gaskets 93. The cinch head bolt has an axial passage 94 terminating in a transverse passage 95, thus effecting communication between the upper side of the discharge valve and the annular chamber in the cinch head formed by the groove 96 in the circumference of the cinch head bolt. Leakage from the cylinder around the piston 75 is prevented by suitable packing held in place by a gland 78 and a gland nut 79.

Forged integrally with the lower end of the cylinder 76 is a block or suction valve housing indicated generally at 100. As shown in Figs. 75

5 and 6, the block 100 is provided with a cut-out portion 101 to receive the eccentric 102. A replaceable bronze block 103 is set into the upper side of the cut-out portion 101 to take the thrust during the working stroke. From this arrangement, it will be apparent that the rotation of the shaft 25 effects a reciprocation of the cylinder 76, the block 100 and the attached parts hereinafter described.

10 The pump inlet valve 105 is carried in the block 100, as shown in Fig. 5, and is urged toward closed position against the valve seat 106 by the spring 107 bearing at one end against the upper face of the valve 105, and at its other end against the lower end of the inlet valve plug 108. Chamber 109, between the upper surface of the valve 105 and the lower end of the plug 108, communicates with the chamber 77 of the cylinder 76 through the ducts 110 and 111. The lower end of the duct 110 is closed by a plug 113. It will be readily apparent from Fig. 6 that access to the valve 105 may be had by removal of the plug 108 threaded into the upper end of the chamber 109.

25 In accordance with the invention, the action of the valve 105 is regulated by the lever or rocker arm 115 shown in elevation in Fig. 5. Arm 115 is pivoted on a pin 116 set into the block 100 near one lower corner. The horizontal arm of the lever 115 carries on its end a knob 117 which is adapted, under certain adjustments of the pump, to engage the lower end of the spindle 118 of the valve 105. The vertical portion of the lever 115 is similarly formed with a knob 119 bearing against the surface of the adjusting spindle indicated generally at 120. As shown in Figs. 6 and 7, the block 100 is cut out to form a circular opening 121 to receive the lower end of the spindle 120, and with a joining vertically disposed slot 122 to permit oscillation of the vertical portion of the rocker arm 115. A stop pin 123 limits the drop of the horizontal arm of the lever 115.

40 Spindle 120 is vertically adjustable in the sleeve 69 and below the shoulder 124, forming a seat for the lower end of the spring 125, is cut to provide an elongated flattened portion 126 which, in conjunction with a high shoulder 127 on the end of the spindle, forms a cam surface controlling the operation of the lever 115. Projecting across the lower end of the opening in the sleeve 69 is a pin 128 positioned against the flat portion 126 in such manner, as indicated in Fig. 5, to prevent rotation of the spindle 120 during vertical movement thereof. The spindle 45 is urged downwardly by the spring 125 resting against the shoulder 124, and bearing at its upper end against a similar shoulder 129 formed in the spindle sleeve 69. The upper end of the spindle 50 is threaded into an adjusting nut 130 having a flange with a knurled surface 131. The lower end of the nut 130 is seated in a suitable recess in the upper side of the frame 65. Downward movement of the spindle 120 is limited by the nut 133 pinned to the upper end of the spindle and adapted to rest, when the spindle is in its lowermost position, on the upper surface of the adjusting nut 130. A screen 135 is fitted over the lower end of the block 100 to prevent the entrance 55 of solid particles in the oil into the working parts of the pump.

From the description in connection with Figs. 3 and 4, it will be apparent that the shaft 25 and the several eccentrics are rotated by the suitable 60 reciprocation or rotation of the operating arms

38 or 55 depending on whether the pump is being mechanically or manually driven. Referring again to Fig. 5, the rotation of the shaft is transformed into straight line motion of the cylinder 76 by the eccentric 102 rotating in the cut-out portion 101 of the block 100.

65 Assume that it is desired to operate the pump so as to obtain a maximum discharge or feed into the pipe connected to the cinch head 90. In this situation, the adjustment of the spindle 120 is 10 as shown in Fig. 5, that is, the spindle in its lowermost position, and the nut 133 rest upon the upper surface of the knurled adjusting nut 130. From the drawings, it will be noted that when the knob 119 on the lever 115 rests against the flattened surface 126 of the spindle 120, the knob 117 is out of contact with the lower end of the spindle 118 of the inlet valve 105. Assume that the downward stroke of the cylinder 76 and the attached block 100 has just begun. At 15 the beginning of the downward stroke of the cylinder 76 the intake valve 105 opens. As the downward stroke of the cylinder progresses, oil from the reservoir is drawn around the inlet valve 105, through the chamber 109 and ducts 110 and 111 into the cylinder chamber 77. During the downward movement of the block 100, the spindle 120 being fixed, the knob 119 rides on the flattened surface 126, and as long as this condition continues the knob 117 in no way contacts nor 20 interferes with the movement of the valve 105. The length of the flattened surface 126 is such that, when the spindle is in its lowermost position, the knob 119 at no time engages the high shoulder 127 on the lower end of the spindle. 25 In this circumstance, it will be seen that when the cylinder 76 and the block reach the lowermost limit, the valve 105 is still open, and a full charge of oil has been drawn into the chamber 77. At the beginning of the upward or discharge 30 stroke of the cylinder, the valve 105 immediately closes, and the full charge of oil in the chamber 77 is forced up through the vertical passage 84 in the stationary piston 75, passed the discharge 35 valve 86, through the aperture 94 in the cinch head bolt, into the chamber within the cinch head 90, and thence into the conduit connecting the pumping unit with the particular part of the machine which is to be lubricated. Operating thusly, the discharge of the pump is a maximum, and the rocker arm 115 in no way interferes with the opening or closing of the discharge valve 40 during either the suction or discharge strokes of the pump.

45 Now let it be assumed that it is desired to adjust the pump so that a minimum quantity of oil will be delivered to the point of use on each discharge stroke. The nut 130 is manipulated so as to raise the spindle 120 to its uppermost position. When the spindle is so raised, the adjustment is such that when the block 100 is in its uppermost position, the under sloping surface 137 on the knob 119 is almost in engagement with the upwardly concave surface 138 on the lower end of the flattened portion 126 of the spindle. 50 At the beginning of the down or suction stroke of the cylinder 76, the inlet valve 105 opens. After the block 100 has been carried downwardly a short distance, the knob 119 rides up over the concave surface 138 onto the high shoulder 55 60 65 70 75 80 85 90 95 100 105 110 115 120 125 130 135 - valve 105 open while the knob 119 is in engagement with the shoulder 127. It will thus be seen that, during the down stroke of the cylinder, the inlet valve is held open by the vacuum normally created in the chamber 77, and is also positively held open by the rocker arm 115. During the down stroke of the cylinder and block a full charge of oil is drawn into the chamber 77.
- At the beginning of the up or discharge stroke of the cylinder, the valve 105 would normally close because of the pressure created in the chamber 77. However, as long as the knob 119 rides on the shoulder 127, the knob 117 engages the lower end of the spindle 118 of the valve 105, and holds the valve open, thus permitting oil from the chamber 77 to flow back through the inlet valve 105 into the reservoir rather than through the discharge valve 86, as would be the case if the inlet valve were closed. Now it will be recalled that the adjustment of the spindle in the present instance is such as to cause the pump to deliver a minimum quantity of oil through the outlet in the cinch head 90. As the up stroke of the cylinder and block continues, the knob 119 rides on the high surface 127, and while the knob and the cam surface 127 are so engaged, the valve 105 is held open by the lever 115, and oil from the chamber 77 is returned to the reservoir. Toward the end of the up stroke of the block, the knob 119 slides down over the concave surface 138 to the flat surface 126. In so doing, the knob 117 is permitted to drop, and the valve 105 closes. At the instant of closure of the inlet valve 105, the discharge valve 86 is opened by the pressure created in the chamber 77, and the remainder of the oil in chamber 77 is forced past the discharge valve, and into the conduits connecting the pumping unit to the machine to be lubricated.
- From the foregoing, it will be seen that when the spindle 120 is in its lowermost position, the delivery of the pump is a maximum, and when the spindle is in its uppermost position the delivery of the pump is a minimum. It will be apparent that to regulate the pump so as to feed quantities of oil varying between the maximum and minimum, all that is necessary is to effect suitable vertical adjustment of the spindle 120.
- It will be observed that the present invention provides a force-feed pump readily adjustable to vary the feed thereof, and of such construction that this result is accomplished without adjusting either the stroke of the cylinder or the position of the fixed piston. This feature of the in-

vention makes the pump particularly suitable for use where it is required to deliver the oil against comparatively high pressures for the reason that the two principal elements of the pump, i. e. the cylinder and the piston, may be of particularly rugged construction and not weakened and subject to more or less rapid wear by reason of the direct association with the pump and cylinder of some elements for effecting adjustment of the pump output. In certain of the appended claims the expression "fixed relation with respect to each other" is intended to define this non-adjustable relationship of the cylinder and the piston.

We claim:

1. A pump of the character described comprising in combination a casing, a fixed piston and a movable cylinder mounted therein, an inlet for the cylinder, a valve for controlling the passage of fluid through the inlet, a spindle having a cam surface thereon supported by the casing, a lever mounted on the cylinder having one portion engaging the cam surface and a second portion cooperating with the valve and acting to hold the valve open during a portion of the discharge stroke of the cylinder, and means to move the spindle axially to adjust the cam to vary the feed of the pump.

2. A pump of the character described comprising in combination a fixed piston, a movable cylinder, an inlet for the cylinder, a valve housing movable with the cylinder and having therein a valve for controlling the passage of fluid through the inlet, a cam, a lever pivoted on the housing and controlled by the cam for holding the valve open during at least a portion of a stroke of the cylinder to vary the feed of the pump.

3. A pump of the character described comprising in combination a casing, a fixed piston and a movable cylinder mounted therein, an inlet for the cylinder, a valve housing fixed to and movable with the cylinder, said housing having a valve therein controlling the passage of fluid through the inlet, a spindle having a cam surface thereon supported by the casing, a lever mounted on the housing having one portion engaging the cam surface and a second portion cooperating with the valve and acting to hold the valve open during at least a portion of the discharge stroke of the cylinder, and means to move the spindle axially to adjust the cam to vary the feed of the pump.
